UNITED STATES PATENT OFFICE.

HERMAN C. BUJACK, OF GARY, INDIANA.

SCREEN-FRAME.

1,257,183.

Specification of Letters Patent. Patented Feb. 19, 1918.

Application filed April 16, 1917. Serial No. 162,251.

To all whom it may concern:

Be it known that I, HERMAN C. BUJACK, a citizen of the United States, residing at Gary, county of Lake, State of Indiana, 5 have invented a certain new and useful Improvement in Screen-Frames, and declare the following to be a full, clear, and exact description of the same, such as will enable others skilled in the art to which it pertains 10 to make and use the same, reference being had to the accompanying drawings, which form a part of this specification.

This invention relates to metal screen frames and has for its object a screen frame 15 made simply of strips of metal provided with interlocking joints.

A further feature of the invention is an arrangement whereby the frame is adjustable either lengthwise or widthwise, or both, 20 by means of the devices hereinafter to be described.

In the drawings,—

Figure 1 is a perspective of the metal window screen sash.

Fig. 2 is a vertical section of the same on the line B—B of Fig. 1.

Fig. 3 is a fragment of the sash strip ends showing them in disassembled relation.

Fig. 4 is a similar view showing them assembled.

Fig. 5 is a section of the interlocking strips showing the joint.

Fig. 6 is a perspective of the screen door frame.

Fig. 7 is a cross section on the line C—C of Fig. 6.

Fig. 8 is a sectional detail of a corner of the door.

Fig. 9 is a cross section of the vertical 40 sash bar showing how the hinges are attached.

Fig. 10 is a cross section of the outside vertical sash bar indicating in detail how the adjustment of width is secured.

The window screen sash is made up of four 45 strips of metal forming a rectangular frame (Fig. 1) and the mid-strip *a* may be utilized to reinforce the frame at the center. This mid-strip comprises a strip of metal of near 50 cylindrical cross section to give strength and having its ends flattened and turned into slots *b* of the side strips of the sash to fasten this mid-strip in place. It is to be noted that the sash strips are turned or folded over 55 in a half roll on the inside (Fig. 2) so as to form a hook-like rim over which the wire

mesh *d* may be bent. The mesh being of stiff wire, remains in this shape and this forms a very simple way of attaching a screen to the sash strips. 60

One of the peculiar features of my invention is the use at corners of a very simple joint, for instance, in Fig. 1 it will be noted that the joint is made a lap joint with the ends of the vertical stripslapping to the 65 outside of the ends of the horizontal strips. In Figs. 3, 4 and 5 the details of the joint are brought out. It is to be noted that each sash strip end is provided with a struck-out tongue *e* and a pair of slots *f*. The slots at 70 one strip end are intended to register with the tongue of the other strip end when the lap is formed. The erect tongue *e* as shown in Fig. 3 can be passed through one of the slots and bent down as shown in Figs. 4 and 75 5. The two slots leave an intervening strip *g* which is more flexible than the ordinary stock.

In Figs. 6, 7, 8, 9 and 10 the adjustable feature is shown applied to a screen door, 80 but would also, of course, be applicable to window screens, if desired. The same half roll on the inside of the sash bars is used for retaining the mesh. The thin metal then continues around a stiff channel bar *h* and 85 is doubled back behind the half roll to make a complete sash bar as is well indicated in Fig. 7. Now, on two sides of the frame the channel bar may abut up against the outside of the hollow sheet metal sash bar. 90 On the other two sides the channel bar is located somewhat in from the outside of the hollow metal sash bar as is well indicated at the right of Fig. 7. A strip of heavy gage metal, preferably shallow V-shape in cross 95 section, designated *i*, is used directly on the inside of the hollow metal sash bar. Threaded bolts *j* pass through the thin metal sash bar, the reinforcing strip *i* and the channel strip *h*. Obviously, by tightening these up 100 more or less the reinforcing bar *i* and the exterior sheathing can be brought more or less near the channel bar, thereby reducing the dimensions of the frame.

From the above description, it is obvious 105 that by having this adjustable arrangement on two sides of the screen that the frame may be made slightly larger than is expected to be used and may be very accurately adjusted to the door or window frame by simply turning down the bolts or screws *j*. The sash strip constructed in the way above de-

scribed makes possible this adjustment for the reason that the parts are merely turned over against each other, not rigidly fastened in place.

5 What I claim is:

1. In a screen frame, a bar in the form of thin metal folded over upon itself to form a hollow bar or sheathing, a reinforcing bar within the same near the outer wall of the 10 sheathing and a supporting frame located farther in the sheathing, and devices for causing said hollow bar or sheathing to contract by drawing the reinforcing bar in toward the said supporting frame.
- 15 2. In a screen frame, the combination of a strip of thin metal folded upon itself to form a hollow bar or sheathing, a supporting frame channel shape in cross section, and a reinforcing bar, the said frame and the reinforcing bar being contained within the 20 folded thin metal strip and threaded bolts

passing through the same for adjusting the width of the hollow bar or sheathing.

3. In a screen frame, the combination of a hollow bar in the form of thin metal folded upon itself, a supporting frame within the same and spaced from the thin metal which forms the outside edges of the door, and threaded bolts for changing the relative position of the thin metal that forms the outside edge of the door and the supporting frame, said bolts having heads protruding through the metal that forms the outside edges of the door so that the bolts may be turned by their heads.

35 In testimony whereof, I sign this specification.

HERMAN C. BUJACK.
